UNITED STATES PATENT OFFICE.

WILLIAM J. GRADY, OF DECATUR, ILLINOIS, ASSIGNOR TO FARIES MANUFACTURING CO., OF DECATUR, ILLINOIS, A CORPORATION OF ILLINOIS.

DESIGN FOR A HANGER FOR LIGHT-REFLECTING BOWLS.

48,517.

Specification for Design.

Patented Feb. 8, 1916.

Application filed November 8, 1915. Serial No. 60,448. Term of patent 3½ years.

To all whom it may concern:

Be it known that I, WILLIAM J. GRADY, a citizen of the United States, residing at Decatur, in the county of Macon and State of Illinois, have invented a new, original, and ornamental Design for a Hanger for Light-Reflecting Bowls, of which the following is a specification, reference being had to the accompanying drawing, forming part thereof.

Figure 1 is a side view of a hanger for light reflecting bowls, showing my new design. Fig. 2 is a front view of the same.

I claim:

The ornamental design for a hanger for light reflecting bowls, as shown.

WILLIAM J. GRADY.
